(No Model.)

J. A. FORT.

INSTRUMENT FOR TREATMENT OF STRICTURES BY ELECTROLYSIS.

No. 552,832.

Patented Jan. 7, 1896.

Inventor.
Joseph A. Fort
by Tolopechne, his attorney.

UNITED STATES PATENT OFFICE.

JOSEPH A. FORT, OF PARIS, FRANCE, ASSIGNOR TO THE DR. FORT'S ELECTROLYSIS SANATARIUM, OF NEW YORK.

INSTRUMENT FOR TREATMENT OF STRICTURES BY ELECTROLYSIS.

SPECIFICATION forming part of Letters Patent No. 552,832, dated January 7, 1896.

Application filed November 7, 1895. Serial No. 568,209. (No model.)

To all whom it may concern:

- Be it known that I, JOSEPH A. FORT, a resident of Paris, France, (temporarily residing in New York city, in the State of New York,) 5 have invented a new and useful Improvement in Surgical Instruments for Treatment of Strictures by Electrolysis, which improvement is fully set forth in the following specification.
- 10 This invention relates to an instrument or device for treatment of strictures of all kinds, as of the urethra, esophagus, uterus, or rectum.
- 15 The object of the invention is to cure or remove such strictures by electrolytic action, causing a disintegration of the false growth, as distinguished from cauterizing, on the one hand, or treatment by the knife, on the other. To this end the instrument is made in the form 20 of a long sound, at about the middle of which, at one side, is a projecting blade, having a curved and smooth edge. The sound is formed preferably of rubber and the blade of platinum. The blade is connected by a 25 conductor running through the interior of the sound with a connecting-screw on the handle of the instrument, and to this screw is attached one wire of an electric circuit, the other wire being attached to a plate, 30 which, in using the instrument, is applied to the body of the patient. The instrument beyond the platinum plate has a very flexible tapering portion, which acts as a guide in leading the instrument, without injury to the 35 membrane, to the constricted part, and the platinum plate or electrode being in contact with this part and the circuit closed through the patient's body the instrument acts upon the stricture by electrolysis, de- 40 composing or disintegrating the tissues. The electrode may be in the form of a bowed or curved wire, and the better to insure the suc- 45 cess of the operation it is preferred to employ two wires, on opposite sides of the sound, so 50 that the instrument acts on both sides of the strictured passage. An advantage of the wire over a rigid blade is that the former yields somewhat to the pressure of the strictured part, and is less likely to cause injury to the membrane.

The accompanying drawings, which form part of this specification, illustrate the manner in which the invention has been carried out in practice.

Figure 1 shows a complete instrument, and 55 Fig. 2 a portion of the sound, the platinum electrode being in the form of a plate.

A represents the rubber sound, the shape of which is of course variable according to the particular use to which the instrument is 60 to be applied, that shown in the drawings being designed for the treatment of strictures of the urethra. The sound terminates in a long slender flexible portion *a*, and at the handle it has a metallic connection device or terminal *b* for attachment of one wire of a circuit, including an electric generator *B*. From the terminal *b* a metallic conductor *c* extends through the body of the sound and connects with the bowed platinum plate or 65 wire *d*, which projects at one side of the sound and constitutes one electrode of the circuit. As shown in Fig. 1, there may be two of these wires, both connected with the conductor *c*. The plate or wire should be curved or bowed, 70 as shown, and have a smooth edge or surface, the object being not to cut or abrade the surface of the membrane, as in the surgical treatment of strictures. In Fig. 2 the platinum electrode is in the form of a curved plate. 75

In operation the sound is introduced carefully into the strictured passage, in this case the urethra, the flexible portion *a* serving to guide the introduction of the instrument, and curling or rolling itself up in the bladder, 80 while the blade or electrode *d* presses against the stricture. The other electrode *D* is then applied to the abdomen or other part of the patient's body near the part operated upon, and the electric circuit is thus completed, 85 the current passing through the stricture and acting electrolytically or electrochemically thereupon.

What I claim as new, and desire to secure by Letters Patent, is—

1. An instrument for treatment of strictures electrolytically, comprising a non-conducting sound having a slender flexible end portion, a curved platinum electrode projecting from the side of the sound intermedi- 90

95

100

ate of the handle and flexible end portion, and a conducting wire extending from the platinum plate or wire to the handle of the instrument, substantially as described.

5 2. An instrument for treatment of strictures, said instrument comprising a non-conducting sound, a bowed platinum wire or wires projecting from the side thereof, and a conductor extending from said platinum
10 wires through the sound to a connection de-

vice or terminal on the handle, substantially as described.

In testimony whereof I have signed this specification in the presence of two subscribing witnesses.

JOSEPH A. FORT.
